(57) **CLAIM**

We claim the ornamental design for a magnetic mounting frame, as shown and described.

DESCRIPTION

FIG. 1 is a front perspective view of a magnetic mounting frame showing our new design;

FIG. 2 is a rear perspective view thereof;

FIG. 3 is a front elevational view thereof;

FIG. 4 is a rear elevational view thereof;

FIG. 5 is a side view thereof; and,

FIG. 6 is a top view thereof.
